H. T. NOWOTNY.
LOCK FOR SCREENS AND THE LIKE.
APPLICATION FILED NOV. 1, 1916.

1,230,920.

Patented June 26, 1917.

UNITED STATES PATENT OFFICE.

HARRIE THOMPSON NOWOTNY, OF ST. LOUIS, MISSOURI.

LOCK FOR SCREENS AND THE LIKE.

1,230,920.

Specification of Letters Patent. Patented June 26, 1917.

Application filed November 1, 1916. Serial No. 128,969.

To all whom it may concern:

Be it known that I, HARRIE THOMPSON NOWOTNY, a citizen of the United States, residing in the city of St. Louis and State of Missouri, have invented certain new and useful Improvements in Locks for Screens and the like, of which the following is a specification.

My invention relates to improvements in locking and latching devices and more particularly to devices of this character which are adapted to be fitted upon screen and other doors.

At the present time there are a number of latching or spring holding devices on the market for the purpose of securing a screen door or the like against accidental opening and at the same time permitting it to be easily pushed open when desired, the latching being accomplished by spring tension only.

Likewise various positive locking devices are on sale and in common use for fastening a door in a secure manner and preventing the opening of the same. To release doors secured by a lock of this class, it is necessary to first release or unlock the lock and then push or pull the door open.

The objects of my invention are to produce a combined locking and latching device which may be utilized when in one position to merely latch the door and when in another position to positively lock the door closed, to so form the device that it may be easily and quickly fitted on and attached to a door and its casing, or removed therefrom, and to provide a construction of simple and inexpensive character possessing reliability, durability and efficiency and capable of being expeditiously and conveniently adjusted by any one from one position to another.

To this end, my improved device consists of two flanged parts, one of which is adapted to be attached in stationary position to a door frame and constitutes or forms an enclosing casing, and the other of which is rotatably mounted on the first mentioned part, a projecting latch attached to the door, and mechanism arranged within the flanged parts and adapted to coöperate with the latch to merely either hold the door or to positively fasten or lock the door in closed position as desired.

I accomplish the above and other objects

of my inventions by certain means and mechanism as hereinafter set forth in the following description and as particularly pointed out in the appended claims, reference being had to the accompanying drawings in which an embodiment or adaptation of my improved device is illustrated.

In the drawings:

Figure 1 is a top plan view of my improvement with the latch inserted in place in the casing and the top cap omitted to disclose the interior construction, but approximately shown in dotted outline to indicate its position.

Fig. 2 is a detached detailed perspective view of the latch.

Fig. 3 is a detached detailed perspective view of top cap.

Fig. 4 is a detached perspective view of one of the gripping or holding arms.

Fig. 5 is a detached perspective view of one of the springs for tensioning the gripping or holding arms.

Fig. 6 represents the perspective view of the assembled device showing the gripping arms within the casing in readiness to receive the latch, and the latch being omitted.

Fig. 7 is a section through the latch on line 2—2 Fig. 1 and illustrating a fragment of the casing, top cap, and the interior mechanism.

Fig. 8 is a fragmentary view similar to Fig. 7 with the latch moved to its locking position.

In referring to the embodiment and adaptation of my invention shown in the accompanying drawings in detail like numerals designate corresponding parts.

My improved device as illustrated comprises two separate parts or members, one of which forms a latch or projection which is fastened to and extends from the door and the other of which constitutes a lock or latch casing that is attached to the door frame and is adapted to receive the latch or projection when the door is closed, being provided with an opening through which the latch is inserted and interior mechanism for retaining said latch therein with a spring tension.

The casing is composed of a lower member having a circular base, 1, and an annular upstanding surrounding flange, 2, and an upper member or cap having a circular top, 3, slightly larger in circumference than the

base, 1, and an annular depending surrounding flange, 4, which telescopes on and fits loosely around the flange, 2, of the lower member when the two members are assembled together in operating position, as shown in Fig. 6.

The flange, 2, I preferably provide with a flattened portion, 5, and form a central vertical slot, 6, therein and diametrically opposite another slot. I cut or otherwise form another and wider slot on opening, 7, see Fig. 1. The top cap is mounted upon the lower member so as to turn or partially revolve thereon and is fastened in place by a center screw, 8, or the like. The lower member is likewise fastened in stationary position to the door frame by screws or other suitable fastenings, 9, as shown in Fig. 1.

20 I cut or otherwise form a slot or opening, 10, in the flange, 4, which registers with the opening, 7, when the device is in its latching position and provide two oppositely extending horizontal recesses, 11, located one on each side of the opening, 10, for a purpose to be hereinafter explained.

The latching and locking mechanism is of extremely simple construction, having two complementary gripping and latching arms 30 which are similar in construction and form and are interchangeable.

These arms are fitted in place in the interior of the casing in opposed position as shown in Fig. 1, and each has one end thereof fitted through the slot, 6. Each of these arms I prefer to make substantially as shown in Figs. 1 and 3 with a bent inner terminal, 12, which extends laterally at a right angle from the inner end of the body 40 of the arm.

The intermediate portion of the body is bent to approximately a V form as shown at 14 in Fig. 1, and the outer extremity, 15, is bent to extend obliquely outward and at 45 nearly a right angle to the outer half portion to the V 14.

When fitted in place the two arms are opposed to each other, as before stated and have their extremities fitted through the 50 slot, 6, with the terminal portions, 12, lapped on the exterior of the flattened portion, 5, and the V portions, 14, forming a substantially four walled space between them.

55 The two oblique portions, 15, provide a V shaped mouth for the easy entrance of the latch or projection as shown in Fig. 1.

To normally retain the arms in their latching position, I provide two springs, 16, 60 each of which is preferably made from a suitable strip of spring metal and substantially, as shown in Fig. 5.

These springs are each fitted in place by bending it in a curved form within the 65 flange 2 of the casing and inserting one end

beneath a hook lug, 16', which is formed integral with and projects laterally out from each of the gripping arms.

A centering lug, 17, which is preferably made integral with the base, 1, extends 70 therefrom into an interposed position between the arms as shown in Fig. 1, and serves to maintain said arms in a centered position.

The latch I also prefer to make in one 75 integral piece of metal and as shown it consists of two lateral end portions, 18, which stand oppositely to each other in approximately the same plane and are fastened to a door, 19, by screws, 20, or the like, a projecting shank, 21, having a notched edge, 22, and an enlarged four sided substantially 80 square head, 23, at the other extremity of the shank which is arranged with one corner in alignment with said shank and forming a pointed or tapering extremity for the 85 same.

To limit the turning movement of the top cap, a bolt, 24, is fitted through an opening, 25, in the flange, 2. Two of these openings are preferably formed in said flange, one being located on one side of the slot or opening, 7, and the other on the opposite side of said slot.

90 A nut, 27, is fitted on the inner projecting end of the bolt substantially as shown in Fig. 1, and serves to lock the bolt in place when said bolt is screwed in. Owing to this construction openings, 25, need not be provided with an internal screw thread. 95 The purpose of the bolt is to form a stop which limits the rotation of the cap as previously stated, and the outer portion of said bolt projects sufficiently to allow a portion of its stem to fit in one of the horizontal recesses, 11, with the head of said bolt projecting beyond the exterior surface of the flange as indicated more particularly in Figs. 1 and 6.

100 This improved device is adapted to serve 110 both as a latching device for holding the latch against accidentally releasing the door and also as a positive lock.

When the device is in the position shown in Figs. 1, 6 and 7, the latch can be inserted 115 in or withdrawn from the casing by pulling or pushing upon the door, as it is held therein merely by the frictional spring tension of the arms. To positively lock or fasten the latch in the casing and thus secure the door 120 in its closed position, the top cap is turned to bring the parts into the position shown in Fig. 8. This causes the shoulders of the notched edge, 22, to engage on opposite sides of the inner surface of the flange as 125 shown in Fig. 8, and thus lock the latch therein.

130 It will be noted that the interior mechanism arranged within the casing serves merely to frictionally engage and hold the

latch in place and that to positively fasten the latch therein, it is necessary to turn an independent element, that is the top cap, which forms a separate independent and 5 manual, adjustable and positive lock.

My improved latching and locking device is applicable to a variety of purposes, for instance, in the present drawings I have shown it as adapted to hold a screen or 10 other door. It may, with equal facility, be applied to a window, a freight car door, and many other like articles. Perhaps the greatest and most advantageous feature possessed by my improved device is that 15 it forms both a latching device and a positive locking device, the two being combined in one, and the mechanism being so arranged that any one can easily change the device from a positive locking device 20 to a mere spring latching position.

While I have described in the foregoing specification adaptations or embodiments of my invention, it should be understood that the structural parts thereof may be 25 varied, changed, modified or altered or one or more may be omitted or dispensed with without departing from the spirit of my invention as fairly defined in the following claims, or as may be imparted thereto by 30 invoking the doctrine of equivalents.

Having thus described my invention what I claim to be new and patentable is:

1. A device of the class described comprising a latch, a casing adapted to receive 35 said latch, and a flanged cap movably fitted on the casing and adapted to positively lock the latch in said casing.

2. A device of the class described comprising a latch, a casing adapted to receive 40 said latch, spring latching mechanism in said casing for said latch, and a cap on said casing for positively locking the latch in said casing, said cap being movably mounted on the casing.

45 3. In a device of the class described, a latch, in combination with a casing having an opening into which the latch may be introduced, spring gripping mechanism in said casing, and a flanged cap on said casing for positively locking said latch in said casing.

4. In a device of the class described, a latch, in combination with a casing having an opening into which the latch may be 55 introduced, spring gripping mechanism in said casing having two gripping arms and tensioning springs for said arms, and a flanged cap on said casing for positively locking said latch in said casing.

60 5. In a device of the class described, a latch, in combination with a casing having an opening into which the latch may be

introduced, spring gripping mechanism having two angularly bent gripping arms arranged in opposite position in the interior 65 of the casing; and curved tensioning springs for said arms, and a flanged cap movably mounted on said casing for positively locking said latch in said casing.

6. In a device of the class described, a latch, in combination with a casing having an opening into which the latch may be introduced, and spring gripping mechanism having two angularly bent interchangeable 75 gripping arms arranged in opposite position in the interior of the casing and curved tensioning springs for said arms, and a flanged cap movably mounted on said casing, said cap having an opening in the flange which is adapted to register with the 80 opening, in the casing through which the latch is fitted.

7. In a device of the class described, a latch, in combination with a casing having an opening into which the latch may be introduced, spring gripping mechanism having two angularly bent gripping arms 85 removably arranged in opposite position in the interior of the casing and curved tensioning springs for said arms, and a positive locking cap movably mounted on the 90 casing.

8. In a device of the class described the combination of a projecting latch attached to a door, a casing secured to a frame and 95 having an opening into which the latch is adapted to be inserted when the door is closed, and a positive locking cap movably carried by said casing and adapted to co-operate with said latch.

9. In a device of the class described the combination of a projecting latch attached to a door, a casing secured to a frame and having an opening into which the latch is adapted to be inserted when the door is 105 closed, latching mechanism within the casing and a positive locking cap movably mounted on the casing.

10. In a device of the class described the combination of a projecting latch attached to a door, a casing secured to a frame and having an opening into which the latch is adapted to be inserted when the door is 110 closed, latching mechanism within the casing and a positive locking cap movably mounted on the casing; said casing and cap having complementary telescoping flanges 115 provided with openings for the insertion of the latch.
